SELECTIVE TRAVEL DRAFT GEAR**Bertil E. Peterson, Chicago, Ill., assignor to Cardwell Westinghouse Company, a corporation of Delaware**

Application November 3, 1955, Serial No. 544,782

9 Claims. (Cl. 213—22)

This invention relates to a shock absorber for railway freight cars and more particularly to a selective travel type draft gear.

The principal object of the invention is to provide a draft gear; that is adapted for use in a standard A. A. R. draft pocket and offers increased travel and capacity in buff; that is adapted for use with standard draft gear attachments; that includes energy absorption means for reducing loading impacts, particularly those associated with buff loads, and dampening recoil effects; and that may be foreshortened for facilitating insertion in the draft gear pocket.

Generally speaking this is accomplished by locating separate cushioning units within the draft pocket on opposite sides of a transverse wall that forms a portion of a novel yoke that is movable within the draft pocket. The yoke is keyed to a conventional coupler for applying draft to the front cushioning unit and supports the front cushioning unit for abutment with the coupler shank for applying buff to both cushioning units in series.

The transverse yoke wall carries a friction wedge bar that is movable therewith and that extends rearwardly thereof for sliding frictional engagement with friction shoes that are housed within suitable pockets formed in a rear follower. The shoes are yieldably urged into contact with the wedge bar so that movement of the yoke relative to the rear follower develops frictional energy dissipation. In addition the draft gear may be foreshortened and held against expansion by keying the wedge bar against movement relative to the rear follower.

Other objects and advantages of the invention will be apparent during the course of the following description.

In the accompanying drawings forming a part of this specification and in which like numerals are employed to designate like parts throughout the same,

Fig. 1 is a horizontal section through familiar parts of a freight car showing the draft gear applied;

Fig. 2 is a vertical section of the same;

Fig. 3 is a horizontal section showing the relations of the relative parts in buff;

Fig. 4 is a horizontal section through familiar parts of a freight car and showing another embodiment of the draft gear applied;

Fig. 5 is a vertical section of the same;

Fig. 6 is a horizontal section showing the relations of the relative parts in buff;

Figs. 7, 8, and 9 are cross-sectional views taken on the lines 7—7, 8—8, and 9—9, respectively, of Fig. 4;

Fig. 10 is a perspective view of the yoke employed with a draft gear in accordance with the second embodiment;

2

Figs. 11 and 12 are perspective views of the front and rear followers, respectively;

Fig. 13 is a perspective view of the wedge bar and shear pin;

5 Fig. 14 is a side view illustrating the manner in which the shear pin mounted in the wedge bar cooperates with the rear follower and temporarily holds the draft gear compressed for handling, shipping, and installing;

Fig. 15 is a capacity curve for the rubber-friction gear 10 of Figs. 4 to 14, in accordance with the standard A. A. R. capacity or drop test, and indicates the high capacity and controlled recoil of the gear; and

Fig. 16 is a fragmentary cross-sectional view corresponding generally to that of Fig. 9, but is taken through 15 a modified rear follower that offers varied energy absorption characteristics.

Referring now to the drawings and particularly to Figs. 1 to 3, a simplified form of draft gear constructed in accordance with the concepts of the invention is designated

20 generally at 20 and is shown applied in a draft gear pocket of standard size in accordance with the requirements of the Association of American Railroads for cars used in interchange. The gear is shown in the familiar surroundings of center sills 21, front and rear draft lugs 22 and 23, 25 respectively, coupler butt or shank 24 slotted as at 25 to receive a horizontal draft key 26 and having a coupler horn 27 spaced forwardly of a striking plate 28 to allow inward travel of the coupler shank, coupler carrier iron 29 and draft gear carrier irons 30. These parts are so 30 familiar that no specific description is deemed necessary.

The present draft gear is of the selective travel type and provides for substantial overtravel in buff while maintaining a total overall travel of 5½ inches as is required for cars used in interchange and these specifications are met

35 without modifying the standard draft gear attachments and associated portions of the car frame. The gear consists of a novel yoke generally indicated at 32 that is movable not only during the application of draft loads but also while buff loads are applied, front and rear cushioning units generally indicated at 33 and 34, respectively, and engaging the opposite faces of a rear transverse wall 35 of the yoke 32, and front and rear follower members 36 and 37, respectively.

40 The yoke is shown, for illustrative purposes only, as being of the vertical-plane, horizontal key type and has its side arms 38 integrally connected to the rear transverse wall 35 by top and bottom wall portions designated 39 and 40, respectively. The yoke, which is preferably of

50 cast steel, is open at its forward face and the coupler shank 24 applies buff loads to the draft gear by direct engagement with the front follower 36. It may be seen that the yoke with the front stops 22 and front follower 36 defines a chamber for the front cushioning unit 33 and with the rear stops 23 and rear follower defines a separate chamber for the rear cushioning unit 34.

55 The front follower 36 is provided with a forwardly offset portion 42 and therefore the coupler is allowed to go endwise relative to the car an increased distance over that commonly permitted in order to space the coupler horn 27 an increased distance from the striking plate 28 and thereby accommodate the additional buff travel desired. As previously stated, the yoke is capable of both forward and rearward movements, and as best seen in Figs. 1 and 3, the yoke is constructed and arranged to accommodate

such movements without creating any conflict with the adjacent portions of the front stops.

The cushioning units 33 and 34 may be of any selected type but are here shown as the rubber spring type and are composed of a plurality of perforated rubber bars 44 on each side of the plates 43 and spacer plates 45 interposed between the cushioning elements. A variety of such rubber spring cushioning elements is known and no detailed description is deemed necessary.

Upon receiving buff loads indicated by the arrow B in Fig. 3 the coupler butt 24 acts against the forward offset 42 of the front follower 36 forcing that follower against the front cushioning unit 33 which in turn transmits the buff forces through the transverse wall 35 of the yoke to the rear cushioning unit 34 which reacts against the rear follower 37 that is in abutting engagement with the rear draft lugs 23. Since the yoke is movable, both cushioning units will yield to provide a relatively long and smooth high energy cushioning action for the buff loads. The movement of the yoke during buff occurs due to forces which are transmitted from the coupler butt through the front cushioning unit to the rear transverse wall 35 of the yoke and no buff loads are applied by the key 26 to the side arms 38 of the yoke.

It should be apparent from Figs. 1 and 2 that when draft loads are applied, the gear functions in the conventional manner in that draft forces are transmitted from the coupler shank 24 to the yoke 32 through the draft key 26. Forward movement of the yoke compresses the front cushioning unit only and allows the rear cushioning unit to expand and take up any slack. Thus draft forces cause the transverse wall 35 of the yoke to move forwardly and compress the front cushioning unit 33 against the front follower 36 which in turn abuts against the front draft gear lugs 22.

Thus the front cushioning unit 33 acts to cushion both buff and draft loads whereas the rear cushioning unit is active only in the case of buff loads. The overall arrangement of the parts is simple and compact and entirely eliminates the necessity of the standard type yoke while at the same time being considerably less expensive to manufacture than comparable selective travel type draft gears.

Another embodiment of a selective travel draft gear is shown in Figs. 4 to 14 and in this case is of the rubber-friction type which not only affords higher capacity both in buff and draft but also reduces impact effects because of its energy absorption characteristics and more importantly limits recoil effects and dampens multiple vibrations of the gear.

The rubber-friction gear of this invention is adapted for application in a standard draft pocket and cooperates with standard draft gear attachments and the freight car frame in substantially the same manner as the gear of Figs. 1 to 3. For ease of description the corresponding parts of the car frame are numbered identically.

The rubber-friction gear also consists of a novel yoke 132 that is movable not only during the application of draft loads but also while buff loads are applied, front and rear cushioning units generally indicated at 133 and 134, respectively, and engaging the opposite faces of a rear transverse wall 135 of the yoke 132, front and rear follower members 136 and 137, respectively, and an energy absorbing friction system 101.

The yoke as shown in perspective in Fig. 10 is again illustrated as being of the vertical-plane, horizontal key type and has its side arms 138 merging with top and bottom wall portions designated 139 and 140, respectively, which extend forwardly from the rear transverse wall 135. Structurally the yoke may be identical with the yoke employed in connection with the embodiment of Figs. 1 to 3; however, for accommodating the energy absorbing system 101, the yoke is provided with a shouldered aperture 102 that extends completely through its rear transverse wall 135.

The front follower 136 shown in perspective in Fig. 11 may also be identical with the follower of the previous embodiment and also includes a forwardly offset portion 142 that spaces the coupler horn an increased distance from the striking plate and permits the desired overtravel in buff.

The rear follower 137, as best seen in Figs. 4, 9, and 12, consists of front and rear plates designated 104 and 105, respectively, that are spaced apart by suitable horizontal reinforcing ribs 106 and vertical reinforcing ribs 107 which are constructed and arranged to define laterally spaced apart opposed friction shoe pockets 108 and 109. The plates 104 and 105 are centrally apertured as indicated at 110 and 111 to receive an elongated wedge bar 112 which is provided with a shouldered head 113 that mounts in countersunk fashion within the shouldered aperture 102 provided in the rear transverse wall 135 and which is formed with a rearwardly tapering portion 114 that telescopes within the apertured rear follower and extends completely therethrough as indicated in Fig. 4.

Each of the friction shoe pockets contains a spring pack 116 that reacts against the vertical rib 107 and applies pressure to a pair of identically shaped wedgelike shoes 117 that are arranged in overlapping relationship within the pocket. Manufacturing advantages are gained from the fact that the vertical ribs 107 are arranged to run parallel with the adjacent surface of the tapered wedge bar since this permits all of the wedge shoes to be shaped identically.

In Figs. 4 and 9 the spring pack 116 is shown in the form of rubber-bar elements secured on opposite sides of a perforated plate, and the arrangement of the pocket, spring pack and shoes is such that when the draft gear is in its normal release position which is the position in which the gear is shown in Figs. 4 and 5, the spring units will be precompressed an amount sufficient to insure that they will operate along the relatively straight line portion of their load deflection curve.

The cushioning units 133 and 134 again may be of any selected type but are here shown in Figs. 4, 7, and 8 as the rubber spring type and are composed of a plurality of perforated plates 143 and rubber bars 144 on each side of the plates 143 and spacer plates 145 interposed between the cushioning elements. It will be noted that the front cushioning unit is of a smaller cross-section than the rear cushioning unit, as is necessary to provide clearance for the top and bottom walls 139 and 140 of the yoke.

In the case of the rubber friction draft gear an extra spacer or backing plate 145 is provided adjacent the forward face of the transverse wall 135, and as will become more clear presently, this additional plate performs the important function of uniformly distributing the transmitted buff loads so that the yoke 132 and wedge bar move rearwardly in unison. Furthermore, the rear cushioning unit is arranged with a longitudinal bore 146 for accommodating the wedge bar 112.

In assembling the gear, the wedge bar 112 is passed through the transverse wall 135 of the yoke so that the shouldered head 113 nests within the shouldered aperture 102 formed in the transverse wall. The rear cushioning unit 134 and rear follower with its friction system already in place therein is telescoped over the wedge bar 112 and the parts are precompressed to a degree sufficient to cause a vertical bore 118 formed adjacent the rear end of the wedge bar to clear the rear wall 105 of the rear follower. The retaining pin 119 may then be inserted in the bore 118 to hold the parts in compressed relation and this is best shown in Figs. 4 and 14. This arrangement greatly facilitates handling, shipping, and installing the draft gear. It should be apparent that after sufficiently compressing the rear cushioning unit, the front cushioning unit will have adequate mounting clearance and may be easily inserted at the time of installation of the gear in a draft pocket.

After the gear is installed, the first buff load will permit

the pin 119 to fall through the bore 118 and release the gear.

When buff loads are applied as indicated by the arrow B in Fig. 6, the coupler butt 24 forces the front follower 136 inwardly to compress both cushioning units as explained in the case of the previous embodiment. This action again results in part from the fact that the entire yoke moves rearwardly and in the present instance this movement of the yoke relative to the rear follower 137 brings into play the energy absorbing system composed of the wedge bar 112 and cooperating friction shoes 117 urged into engagement therewith by the spring packs 116. The portion of the buff load which is not absorbed by the front cushioning unit is transmitted by the backing or spacer plate 145 adjacent the yoke wall and urges both the yoke and the wedge bar rearwardly. Thus there is relative sliding movement between the wedge bar 112 and the friction shoes, and due to the lateral pressures existing therebetween, a regulated amount of energy is dissipated frictionally.

Furthermore, due to the tapered arrangement of the wedge bar, the friction forces increase in the case of the larger buff loads which necessarily produce a greater buff travel. The energy absorbed by the friction system effects important reductions in the impacts that are actually transmitted to the car but even more importantly the friction system is operative during both inward and outward movement of the wedge bar so that the energy of recoil resulting from severe buff loads is also dissipated frictionally.

In the case of draft loads only the front cushioning unit will be compressed, but the forward movement of the yoke wall, through shouldered engagement, carries the wedge bar forwardly and once again results in relative movement between the wedge bar and wedge shoes so that the gear also dissipates a portion of the energy of the draft load. In this case, however, the friction forces are somewhat reduced with respect to the forces associated with buff loads. Even in the case of draft the energy of recoil is dissipated frictionally.

In one form of the rubber-friction draft gear, the arrangement gives up to $3\frac{1}{16}$ inches travel in buff and $1\frac{1}{16}$ inches travel in draft—in all a total of $5\frac{1}{2}$ inches which is in accordance with the standards of the Association of American Railroads. The pressures acting on the faces of the wedge shoes in full buff are 4600 pounds, in full draft 1500 pounds, and in neutral position 2400 pounds. This gear offers the relatively high capacity of approximately 50,000 foot pounds in buff and 17,000 foot pounds in draft with controlled recoil, and this also compares favorably with the requirement of the Association of American Railroads that a draft gear be capable of withstanding 18,000 foot pounds in buff.

A typical capacity curve for the gear is shown in Fig. 5. This curve is based on the standard A. A. R. capacity or drop test and the cross hatched area 120 between the closure curve 121 and recoil curve 122 represents the amount of energy absorption. Furthermore, the recoil curve indicates only a 22½ percent recoil so that when the buff loads are removed from the gear, it almost immediately returns to its neutral position with but a minimum of undesired vibrations.

As to the details of construction, the yoke is preferably made of cast steel; the spacer plate adjacent the yoke wall is preferably a $\frac{1}{4}$ inch steel plate. The friction shoes and wedge bar may be of mild steel or hardened steel and the rubber elements in the spring packs and in the cushioning units should be of approximately 72 durometer hardness.

The spring packs which urge the shoes into frictional engagement with the wedge bar may take other forms in accordance with the desired energy dissipation characteristics. One such obvious modification involves the use of a coil spring in lieu of the rubber spring units and if desired the spring pockets 108 and 109 could be en-

larged by appropriately modifying the rear follower 137 in order to accommodate springs of desired capacity.

Another possible modification is shown in the fragmentary view of Fig. 16 wherein the rear follower is modified to accommodate a hydraulic system for loading the friction shoes. In this arrangement the friction pockets 108 and 109 are cylindrical in form and constitute cylinders for the reception of a pair of opposed main pistons 124. The pistons 124 are hollowed as at 10 125 and these chambers 125 communicate at their outer ends with the cylinders 108 and 109 through restricted ports 126 arranged in an annular ring in the piston wall. The chambers 125 receive a secondary piston 127 and a return spring 128. The secondary piston slides back 15 and forth in the chamber 125 while a suitable O-ring 131 prevents undesired leakage.

The cylinders are filled with a suitable fluid 127 and a bias spring 128 and are sealed at their outer ends by suitable plates 129 that are affixed to the follower 137. 20 Leakage at the inner ends of the cylinders is prevented by suitable O-rings 130 provided on the piston 124.

When loads are applied to a gear having this hydraulic system for loading the friction shoes, movement of the wedge bar 112 in the rearward direction is resisted by 25 friction between the shoes 117 and the wedge bar and this is dependent upon the functioning of the hydraulic system. If the loads are sharply applied large pressures are developed since the inward movement of the main piston is completed in a short time and by this time 30 the volume of hydraulic fluid displaced by such movement must pass through the restricted ports 126 and into the hollowed chamber. Less suddenly applied loads, though of comparable magnitude, develop lower friction shoe pressures.

35 The pressures developed by any particular load may, of course, be regulated by varying the size of the ports and/or the viscosity of the hydraulic liquid.

It should be understood that this specific description of the invention is for the purpose of complying with 40 Section 112 of Title 35 of the U. S. Code, and that the appended claims should be construed as broadly as the prior art will permit.

I claim:

1. In a railway car, the combination with a draft pocket 45 having spaced stops therein; of a pair of cushioning units lying in line within the pocket with their remote ends reacting between said stops when in their release position, front and rear follower members between the remote ends of said units and the stops, a yoke having a 50 transverse rear wall mounted in said pocket for movement in either longitudinal direction from its release position, said rear wall lying between and in contact with the adjacent ends of the units and having an open front end, a coupler having a shank attached to the yoke for applying draft to the front one of said cushioning units through 55 said yoke and movable through the open front end of said yoke for abutting engagement with the said front cushioning unit whereby both of said units operate in buff and only said front unit operates in draft, and energy 60 dissipating means comprising first friction means mounted in thrust engagement with said yoke and movable therewith and second friction means carried by said rear follower said first friction means extending through the rear one of said cushioning units into cooperating engagement with said second friction means whereby relative movement between said yoke and said rear follower causes relative movement between said first and second friction means to develop a frictional dissipation of energy.

- 70 2. In a railway car, the combination with a draft pocket having spaced stops therein; of front and rear cushioning units lying in line within the pocket with their remote ends reacting between said stops when in their release position, front and rear follower members 75 between the remote ends of said units and the stops, a

yoke having a transverse rear wall mounted in said pocket for movement in either longitudinal direction from its release position, said rear wall lying between the adjacent ends of said cushioning units, said yoke including connection means extending forwardly from said rear wall, a wedge bar in thrust engagement with said yoke and movable therewith, said wedge bar extending rearwardly from said transverse wall through said rear cushioning unit and said rear follower member, said wedge bar having opposed friction surfaces converging toward said rear follower member, transversely spaced friction shoes carried by said rear follower and yieldably engaging the friction surfaces of said wedge bar, and a coupler having a shank in lost-motion connection with said connection means of the yoke, said shank being in thrust relation with the front one of said cushioning units for applying buff forces to said rear unit through said front unit, said lost motion connection accommodating rearward movement of said coupler shank relative to said yoke.

3. In a railway car, the combination with a draft pocket having spaced stops therein; of front and rear cushioning units lying in line within the pocket, front and rear follower members between the remote ends of said units and the stops, a movable yoke having a transverse wall lying between the adjacent ends of the cushioning units, a shouldered wedge bar countersunk in said transverse wall and extending rearwardly through said transverse wall, said rear cushioning unit, and said rear follower member, said wedge bar having opposed friction surfaces converging toward said rear follower member, a backing plate between the front cushioning unit and the transverse wall for moving said yoke and wedge bar rearwardly in unison, friction shoes carried by said rear follower and yieldably engaging the friction surfaces of said wedge bar, and a coupler having a shank in lost motion connection to the yoke for applying draft to said front cushioning unit through said yoke and positioned in abutting engagement with said front cushioning unit to apply buff directly thereto whereby both of said units operate in buff and only said front unit operates in draft.

4. In a railway car, the combination with a draft pocket having spaced stops therein; of a pair of cushioning units lying in line within the pocket with their remote ends reacting between said stops when in their release position, front and rear follower members between the remote ends of said units and the stops, a yoke having a transverse wall mounted in said pocket for movement in either longitudinal direction from its release position, said rear wall lying between and in contact with the adjacent ends of the units, a coupler having a shank attached to the yoke, and energy dissipating means comprising first friction means mounted in said yoke and movable therewith and second friction means carried by said rear follower, at least one of said friction means extending through the rear one of said cushioning units into cooperating engagement with the other friction means whereby relative movement between said yoke and said rear follower causes relative movement between said first and second friction means to develop a frictional dissipation of energy.

5. The arrangement of claim 4 wherein one of said friction means comprises a wedge bar having opposed friction surfaces converging towards the other of said friction means, said other friction means comprising friction shoes yieldably urged into contact with said friction surfaces whereby relative inward movement of said yoke and said rear follower causes relative inward movement between said first and second friction means to develop progressively increasing energy dissipation and relative outward movement of said yoke and said rear follower causes corresponding outward movement of said friction means and develops a progressively decreasing energy dissipation therebetween.

6. In a railway car of the type having a center sill carrying spaced front and rear lugs defining a draft pocket and having a coupler movable into and out of said pocket in response to buff and draft loads respectively; a draft gear for mounting in said pocket and comprising a yoke having a transverse rear wall and transversely spaced arms extending forwardly from said wall for lost-motion connection to said coupler, said arms being spaced apart on opposite sides of said coupler to define therebetween a central opening greater in cross section than said coupler to allow movement of said coupler through said yoke arms towards said rear wall, said yoke being mounted in said pocket for movement in either longitudinal direction from its release position, front and rear cushioning units in line on opposite sides of said transverse wall with the adjacent ends of said units reacting against said wall and with the remote ends of said units reacting between said lugs when said gear is in its release position, a rear follower between said rear cushioning unit and said rear lugs and forming a transverse wall, friction shoes mounted in one of said transverse walls in transversely spaced relationship and yieldably urged towards each other, and a friction bar in thrust engagement with the other of said walls and extending therefrom through said rear cushioning unit into engagement between said shoes.

7. In a railway car of the type having a center sill carrying spaced front and rear lugs defining a draft pocket and having a coupler movable into and out of said pocket in response to buff and draft loads respectively; a draft gear for mounting in said pocket and comprising a yoke having a transverse rear wall and transversely spaced arms extending forwardly from said wall for lost-motion connection to said coupler, said arms being spaced apart on opposite sides of said coupler to define therebetween a central opening greater in cross section than said coupler to allow movement of said coupler through said yoke arms towards said rear wall, said yoke being mounted in said pocket for movement in either longitudinal direction from its release position, front and rear cushioning units in line on opposite sides of said transverse wall with the adjacent ends of said units reacting against said wall and with the remote ends of said units reacting between said lugs when said gear is in its release position, a rear follower between said rear cushioning unit and said rear lugs, friction shoes mounted in said follower in transversely spaced relationship and yieldably urged towards each other, a friction bar in thrust engagement with said yoke and movable therewith, said bar extending rearwardly from said transverse wall through said rear cushioning unit and into said rear follower into engagement between said shoes.

8. In a railway car of the type having a center sill carrying spaced front and rear lugs defining a draft pocket and having a coupler movable into and out of said pocket in response to buff and draft loads respectively; a draft gear for mounting in said pocket and comprising a yoke having a transverse rear wall and loop-shaped arms extending forwardly in transversely spaced relation from opposite edges of said wall to form a pair of transversely spaced apart rearwardly facing cooperating abutment surfaces, said rear wall having a central aperture bounded by forwardly facing internal shoulders, a shouldered wedge bar countersunk in said rear wall in abutting engagement with said internal shoulders and extending rearwardly therethrough, a front cushioning unit reacting between said rear wall and said cooperating abutment surfaces, a rear cushioning unit telescoped over said rearwardly extending wedge bar with its forward end reacting against said rear wall, a rear follower telescoped over said rearwardly extending wedge bar to bear against the rear end of said rear cushioning unit, transversely spaced friction shoes carried by said rear follower and yieldably urged into engagement with said wedge bar, said wedge bar having a slot adjacent

its rear end and said cushioning unit being compressible to expose said slot behind the rear follower, and a keying element in said slot and overlying said rear follower to hold the gear together with said rear cushioning unit under compression.

9. A movable yoke comprising a transverse rear wall providing forwardly and rearwardly facing spring seat surfaces and loop-shaped arms extending forwardly in transversely spaced relation from opposite edges of said wall to form a pair of rearwardly facing cooperating abutment surfaces, each of said arms having a portion extending forwardly of said abutment surfaces having mating longitudinal slots.
